Patented Feb. 15, 1916.

UNITED STATES PATENT OFFICE.

MICHELANGELO BONO, OF NEW YORK, N. Y.

BRAKE ATTACHMENT FOR SEWING-MACHINES.

1,171,410.

Specification of Letters Patent. Patented Feb. 15, 1916.

Application filed June 17, 1915. Serial No. 34,634.

To all whom it may concern:

Be it known that I, MICHELANGELO BONO, a citizen of Italy, and a resident of New York city, in the county and State of New York, have invented certain new and useful Improvements in Brake Attachments for Sewing-Machines, of which the following is a specification.

This invention relates to an attachment for sewing machines by means of which the operator can readily brake the hand wheel with his elbow, and without changing his position. In this way the necessity of grasping the wheel for the purpose of stopping or slowing down the machine is obviated, so that the braking manipulation is greatly facilitated.

In the accompanying drawing: Figure 1 is a side view of a brake attachment embodying my invention; Fig. 2 a front elevation; Fig. 3 a plan; Fig. 4 a detail of the link and adjoining parts; Fig. 5 a section on line 5—5 Fig. 4 and Fig. 6 a detail of the slideable clasp.

From the table or support 1 of the sewing machine, projects the head 2, carrying the hand wheel 3 as usual. To the end of head 2 there is pivoted at 4 a lever or movable member 5 the rear end of which is adapted to be drawn down by a spring 6. To lever 5 is secured by screws 7, a brake beam 8 having a pair of slots 9, for accommodating the screws. This beam bears the brake shoe 10, which is preferably made of rubber or similar flexible material, and which is adapted to engage wheel 3. By means of screws 7, and slots 9, the dip of the brake beam may be adjusted, so that in this way the shoe may be set to engage the wheel at the most effective angle, while furthermore such adjustment may be changed whenever the shoe has become worn. The front of lever 5 is apertured for the reception of a pin 11, having an upper threaded section which is engaged

by the correspondingly threaded hollowed shank of a nut 12. The lower end of pin 11, extends below lever 5 and is provided with an elongated foot 13, passing through a correspondingly elongated slot 14, which is formed in the upper bent part of a link or member 15. Normally, foot 13 extends transversely across slot 14, so that in this way the link is operatively connected to the lever. Link 15 projects downwardly through

a slot of table 1, and is here furnished with

a hook 16 which is engaged by a transverse lever 17 extending along the right side of table 1 and pivoted at its rear end to said table by staple 18. The front end of transverse lever 17, is interlocked with a longitudinal lever 19 extending along the front of table 1, and pivoted at its left end to said table by a staple 20. Lever 19 is loosely straddled by a slideable clasp 21, having a grooved seat 22, that receives an axially slideable shank 23 which projects with its rear end beneath the table, while its front end extends a distance therebeyond and is provided with a tapped eye 24. This eye receives the threaded stem 25 of a vertically movable button or operative element 26, arranged in proximity to the front edge of the table and adapted to be engaged by elbow of the operator's right arm, while said arm is resting upon the table. When the latter presses upon the button which by the construction described is located in proximity to the plane of the table at the edge thereof, he will by shank 23, levers 19, 17 and link 15, tilt lever 5, on pivot 4, so as to throw shoe 10 against wheel 3 and brake the machine. When the operator releases the button, the parts will be returned to their normal or inactive position by means of the spring 6 the hand wheel 3 thus constituting likewise a brake wheel.

The device besides furnishing means for adjusting the tilt of the brake beams, is capable of various other adjustments. Thus by turning nut 12, lever 5 may be so set as to carry the brake shoe nearer to or farther away from wheel 3, so that in this way, the play of the brake shoe may be regulated.

The laterally slideable clasp 21 together with the longitudinally slideable shank 23, permits button 26 to be so set, as to be well under the elbows of operators having different arm-lengths, while by turning the button, 26, the height to which it projects above the table, may be changed. Whenever it is desired to throw the head of the machine back, pin 11 is so turned as to bring its foot 13 into alinement with slot 14 of link 15 whereby that part of the device which is carried by the head will become disconnected from that part which is carried by the table, so that in this way, the head may be moved independently of the table.

I claim:

1. A brake attachment for sewing ma-

- chines comprising a support, a machine head mounted thereon, a brake wheel carried by the head, a movable member operatively connected to the head, a brake shoe carried by said member and adapted to engage the wheel, and a vertically movable operative element arranged in proximity to the plane of the support at the edge thereof and operatively connected to said movable member.
10. 2. A brake attachment for sewing machines comprising a support, a machine head mounted thereon, a brake wheel carried by the head, a lever pivoted to the head, a brake shoe mounted on the lever and adapted to engage the wheel, and a vertically movable operative element arranged in proximity to the plane of the support at the edge thereof and operatively connected to said lever.
15. 3. A brake attachment for sewing machines comprising a support, a machine head mounted thereon, a brake wheel carried by the head, a lever pivoted to the head, a brake beam adjustably secured to the lever, a brake shoe seated on said beam and adapted to engage the wheel, and an operative element arranged in proximity to the plane of the support at the edge thereof and operatively connected to said lever.
20. 4. A brake attachment for sewing machines comprising a lever fitted to a sewing machine head, a brake shoe operatively connected to said lever, a threaded pin engaging the lever and having an elongated foot, a nut carried by the pin, a link having an elongated slot engaged by said foot, a lever operatively connected to the link, and arm-
25 controlled means located at the front of the sewing machine table for operating said last named lever.
5. A brake attachment for sewing machines comprising a lever fitted to a sewing machine head, a brake shoe operatively connected to said lever, a link depending from the lever, a transversely arranged lever engaging the link, a longitudinally arranged lever extending along the front of the table and engaging the transverse lever, and an arm-controlled button operatively connected to the longitudinal lever.
- 45 6. A brake attachment for sewing machines comprising a lever fitted to a sewing machine head, a brake shoe operatively connected to said lever, a link depending from the lever extending along the front of the table and a longitudinally arranged lever operatively connected to the link, a clasp movably mounted on the longitudinal lever, and an arm-controlled button having a shank that engages said clasp.
- 50 7. A brake attachment for sewing machines comprising a lever fitted to a sewing machine head, a brake beam adjustably mounted on the lever, a brake shoe carried by said beam, a link adjustably and removably secured to the lever, a transversely arranged lever engaging the link, a longitudinally arranged lever extending along the front of the table and engaging the transverse lever, a clasp movably mounted on the longitudinal lever, and an arm-controlled button having a shank that slidably engages the clasp.
